UNITED STATES PATENT OFFICE

125,112

DESIGN FOR A BURNER FOR A COOKSTOVE OR THE LIKE

Herbert M. Reeves, Kankakee, Ill., assignor to Florence Stove Company, Gardner, Mass., a corporation of Massachusetts

Application June 24, 1940, Serial No. 93,209

Term of patent 7 years

To all whom it may concern:

Be it known that I, Herbert M. Reeves, a citizen of the United States, residing at Kankakee,
in the county of Kankakee and State of Illinois,
have invented a new, original, and ornamental
Design for a Burner for a Cookstove or the like,
of which the following is a specification, reference being had to the accompanying drawing, forming a part thereof.

Figure 1 is a top plan view of a burner for cook
stove or the like, embodying my new design.

Figure 2 is a side elevational view of the same.
The dominant features of my design reside in the portions shown in full lines.

I claim:

The ornamental design for a burner for a cook-stove or the like, substantially as shown and described.

HERBERT M. REEVES.
